RETAINING BAR FOR LOOM SPOOLS

Application filed April 14, 1930. Serial No. 444,275.

The present invention relates generally to the art of weaving tufted fabrics and more particularly to an improved device for separating the yarns during the spooling operation and retaining the yarn ends in predetermined spooled relation.

In the preparation of loom spools for use in looms for weaving tufted fabrics one of the initial steps consists in making a set-up according to colors, this being done upon a setting frame carrying the required number of yarn reels of different colors. The loom spool to be wound is placed in the frame and the operator then leads the yarns to the spool one at a time and in colors according to the predetermined pattern until the entire length of the spool consists of a plurality of yarns placed side by side. Between the yarn reels and the loom spool there is a place provided on the frame to receive a comb-like retaining bar, one being used for each loom spool and all consisting (as heretofore constructed) of a relatively narrow strip having a top edge provided with parallel teeth. The spaces between these teeth serve respectively as guide slots for the yarns as they are fed to the loom spool during the winding operation, and each slot has a uniform width sufficient to allow each yarn strand to travel freely therethrough without placing the yarn under such tension as to cause a break therein. Since the aforesaid slots have an appreciable width for the purpose above mentioned it is obvious that the yarns can easily slide out of the slots and thus make it impossible to correctly transfer the yarn ends to the tuft frame guides in the predetermined order. To overcome this difficulty it has been the practice heretofore to provide a cover strip which fits over the ends of the teeth and is clamped to the retaining bar so that there is less chance of the yarn ends working out of the retaining bar. This cover strip is applied to the retaining bar after the winding of a loom spool is completed and then the retaining bar and its cover strip are taken out of the setting frame and attached to the filled spool ready for transfer to a tuft yarn frame. Retaining bars of this prior type have been found to have many practical dis-

advantages, for example it is a troublesome step to place the cover strips on the bars; the cover strips being long and flexible are easily bent out of shape and fail therefore to fit over the bars in the required manner; distorted cover strips leave portions of the bars uncovered and the yarn ends come out of the slots; and also trouble is experienced with the devices for interlocking the strips and bars and frequently only one end of the strip is latched in position and the other being free falls away from the bar and leaves the yarn ends unfastened.

Some of the objects of the present invention are to provide an improved yarn retaining bar for loom spools; to provide a retaining bar wherein all of the yarn strands are free to be drawn through the bar during the spool winding operation; to provide a retaining bar wherein the yarn strands are prevented from working loose and becoming disconnected therefrom; to provide a retaining bar which does not require the use of a cover strip; to provide a yarn retaining bar having a means for clamping the yarn strands in set position; to provide a retaining bar which is not only simple and economical to make but is efficient in operation; to provide a retaining bar wherein a locking device is incorporated which does not require separate assembling after the yarn strands are set; and to provide other improvements as will hereinafter appear.

In the accompanying drawings Fig. 1 represents a side elevation of retaining bar embodying one form of the present invention; Fig. 2 represents a side elevation of a yarn clamp forming a part of the present invention and incorporated in the retaining bar; Fig. 3 represents a section on line 3-3 of Fig. 1; Fig. 4 represents a detail in side elevation of the bar broken away to show the operative position of the yarn clamp; Fig. 5 represents a stamped blank from which the bar is formed; and Fig. 6 represents a plan of a wound spool showing the retaining bar in place.

Referring to the drawings one form of the present invention consists of a bar 10 preferably formed by stamping it out of sheet metal

and bending its opposite side edges to form a relatively flat tubular strip of narrow elongated shape. During the stamping operation the blank 11 of Fig. 5 is formed with a 5 row of parallel narrow slits 12 respectively open at both ends into holes 13 each having substantially the same diameter as a yarn strand while the slits 12 are of less width than the strand diameters. When the 10 punched blank is bent along the median transverse line of the slits 12, the holes 13 in the two folded over sides are respectively in register and provide a double row of holes spaced from the top edge of the bar while 15 the top edge itself is in the form of a row of teeth 14 in relatively close spaced relation. Thus each yarn strand can be readily drawn through its slit 12 to take its slidable position in a hole 13.

20 In connection with the retaining bar proper it should be noted that this bending over of the two parts of the punched blank results in the formation of two spaced strips arranged opposite each other but interconnected along one edge. The said strips as well as the bridging portion thereof is slitted in order to provide a comb formed of two opposite spaced rows of teeth. Each slit 12 communicates with a hole 13 of greater 25 diameter than the width of the slit to allow the strand to fluff out to near its normal diameter so that the strands respectively resist working out of the slits but are still held by the bounding wall of the holes against movement in the direction of the strand length. The outer ends of the teeth of one row are curved to meet the similarly but opposite curved outer ends of the other row of teeth and the resulting structure gives the new 30 and advantageous result of gripping each strand of yarn at two places whereby the chance of the strands working outwardly between the teeth is remote even though no further anchoring means is provided.

40 In order to anchor the row of yarn strands to the retaining bar 10 so that each is prevented from any movement with respect to the bar 10, a clamping latch 15 is provided which in the form of the invention here illustrated consists of an elongated narrow body member having one edge thereof provided with teeth 16 which correspond in number and width to the number and width of the teeth 14, but here the teeth 16 are beveled 45 on one side so that the inlet end of each of the slots 17 between the teeth 16 is wider at the open end than it is at the closed end. This ensures each strand easily entering its slot 17 and reaching a hole 13 in order to be 50 gripped by the latch 15 when the latter is moved longitudinally of the bar 10. The tubular construction of the bar 10 provides a narrow through passage in which the clamp latch 15 may slide and which also serves to 55 retain it always connected to the bar 10. The

length of the latch 15 is such as to project from one end of the bar 10 when in unlatched position, and to project from the other end of the bar 10 when it is in latched position. This latter projection is used to automatically release the latch by having the latch end engage a part of the tuft frame when the spool is being attached thereto, whereby it is moved in the required direction to unlock all of the yarn strands simultaneously.

70 It will now be apparent that a complete unitary retaining bar has been devised for separating and holding strands of tuft yarn wherein a plurality of narrow slits allow the respective yarn strands to be drawn down into holes which allow free feeding travel of the yarn during its winding upon a loom spool. Since the slits are narrower than the slots between the teeth of the ordinary retaining bar, the yarn strands cannot work loose and hence the ordinary clamp cover member is dispensed with. After a spool is wound the yarn strands are severed between the retaining bar and the reel spools, and then to ensure against pulling out of the yarn ends through the guide holes it is desirable to shift the clamp latch in the direction to interlock the yarn strands. This movement of the latch causes it to project at one end of the bar and thus it can be readily shifted back to unlatched position by manually pushing this projection end or causing it to engage a cam part on the transfer machine.

75 Having thus described my invention, I claim:

1. A tuft yarn retaining bar consisting of a bar formed by two oppositely disposed strips in spaced relation and interconnected along one edge thereof, said bar having yarn receiving slits in the interconnected portion and strips whereby each strand of yarn is held at 80 two places.

2. A tuft yarn retaining bar consisting of a bar of tubular form having a comb along one edge formed of double teeth providing two rows of yarn receiving slits in spaced relation whereby each strand of yarn is held at 85 two points.

3. A tuft yarn retaining bar consisting of a bar formed by two oppositely disposed strips in spaced relation and interconnected along one edge thereof, said bar having yarn receiving slits in the interconnected portion and strips whereby each strand of yarn is held at 90 two places, and a latch slidably mounted between said strips for simultaneously locking all of said strands in said slits.

4. A tuft yarn retaining bar consisting of a bar having a row of holes transversely thereof and each of an area substantially equal to the thickness of the strand of yarn to be wound, and also having a plurality of slits opening respectively into said holes and each of a width less than the thickness of said 95 yarn strand, whereby each strand of yarn can 100

be compressed to enter said holes by way of said slits and undue play of the strand with respect to the bar is prevented by the normal thickness of the strand filling the holes.

5 5. A tuft yarn retaining bar consisting of a bar having two sides arranged in fixed spaced relation, said sides being respectively provided with slits, the slits in one side registering respectively with the slits in the opposite side.

10 6. A tuft yarn retaining bar consisting of a bar having a row of holes transversely thereof and each of an area substantially equal to the thickness of the strand of yarn 15 to be wound, and also having a plurality of slits opening respectively into said holes and each of a width less than the thickness of said yarn strand, in combination with a latch for locking strands of yarn respectively in said 20 holes.

Signed at Philadelphia, county of Philadelphia, State of Pennsylvania, this 1st day of April, 1930.

ROBERT E. VICKERMAN.
